US0D1035762S

(12) **United States Design Patent** (10) **Patent No.:** **US D1,035,762 S**
(45) **Date of Patent:** **** Jul. 16, 2024**

(54) **SMART GLASSES**

(71) Applicant: **Vuzix Corporation**, West Henrietta, NY (US)

(72) Inventors: **Tyler W. Porter**, Honeoye Falls, NY (US); **Shane Porzio**, West Henrietta, NY (US); **Devrin Talen**, West Henrietta, NY (US)

(73) Assignee: **Vuzix Corporation**, West Henrietta, NY (US)

(**) Term: **15 Years**

(21) Appl. No.: **29/851,995**

(22) Filed: **Sep. 1, 2022**

(51) LOC (14) Cl. **16-06**

(52) U.S. Cl.

USPC **D16/326**; D16/309; D14/372

(58) **Field of Classification Search**

(57) **CLAIM**

The ornamental design for smart glasses, as shown and described.

DESCRIPTION

FIG. 1 is a top, front, left side perspective view of a new and ornamental design for smart glasses, showing our new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a bottom, front, left side perspective view thereof; and,

FIG. 9 is a bottom, front, right side perspective view thereof. The broken lines shown in the figures depict portions of the smart glasses that form no part of the claimed design.

1 Claim, 9 Drawing Sheets
